BARBER'S COAT

Filed Dec. 12, 1931

UNITED STATES PATENT OFFICE

ISADORE GOLDMAN AND JACOB COHEN, OF CHICAGO, ILLINOIS

BARBER'S COAT

Application filed December 12, 1931. Serial No. 580,540.

In barber shops, beauty parlors and other similar establishments where hair is trimmed and cut, it has been the custom and a requirement that the barbers or attendants wear washable coats, smocks or gowns which are usually provided with the ordinary type of concealed or patch pockets which are provided with longitudinal or top openings for the reception of barber appliances or other articles. With the open top types of pockets in garments of the type hereinbefore referred to, it has been found that during hair cutting operations small particles or lengths of hair find their way into the open top pockets and gradually accumulate therein. When the coats, smocks or gowns are soiled and are sent to a laundry or clean coat service company, it is necessary to employ additional help for the purpose of removing or cleaning out the hair which has accumulated in the garment pockets. Even by turning the pockets inside out and thoroughly brushing the same, it has been found almost impossible to remove all of the short hair clippings so that after the garments are laundered and delivered for further use, hair clippings still may be found in the creases and seams within the pockets. It will thus be noted that even with clean garments that an unsanitary condition is met since combs, brushes, clippers, scissors and the like which are inserted into the pockets come in contact with the old hair clippings which may carry disease germs which are liable to be transmitted to the heads of customers or to the hands of the operators with the repeated insertion of the operator's hands into the garment pockets.

In order to obviate the above mentioned unsanitary conditions, this invention has been devised for the purpose of providing barber coats, smocks or gowns with improved sanitary pockets which are closed at the top and are provided with side or vertical entrance openings so that the entrance of hair clippings into the pockets is substantially elim-

inated, thereby producing a more sanitary garment both from the operator's standpoint and for the protection of the customers and patients. With the provision of side or vertical openings in the garment pockets, the accumulation of hair clippings in the pockets is obviated thereby making it unnecessary to provide additional help in laundries and the like for the purpose of removing hair clippings from the pockets prior to the laundering of the garments. 50

It is an object of this invention to provide a barber's or beauty parlor attendant's coat, smock or gown with sanitary pockets constructed to obviate the accumulation of hair 60 clippings therein.

It is also an object of this invention to provide a barber's garment having pockets provided with closed tops and side openings.

It is a further object of this invention to provide a hair cutter's garment with improved pockets which are closed at the top and have side openings to reduce the accumulation of hair clippings therein to a minimum, said pockets being so constructed that prior to the laundering thereof they may be opened out to facilitate thorough cleaning of the same. 70

It is an important object of this invention to provide a sanitary barber's coat, smock or gown having improved sanitary inner or outer pockets constructed to eliminate the possible accumulation of hair clippings therein by providing the pockets with closed tops and side openings, with said pockets being either 80 of the permanently attached type or of a demountable or openable construction, to facilitate thorough cleaning thereof prior to the washing and ironing of the garment. 75

Other and further important objects of this invention will be apparent from the disclosures in the specification and the accompanying drawing. 85

The invention (in a preferred form) is 90

illustrated in the drawing and hereinafter more fully described.

On the drawing:—

Figure 1 is a view of an attendant wearing a washable barber's coat having improved sanitary pockets embodying the principles of this invention.

Figure 2 is an enlarged fragmentary sectional view of a portion of the garment illustrating one of the improved closed top and side opening pockets.

Figure 3 is a vertical detail section of the pocket taken on line III—III of Figure 2.

Figure 4 is a horizontal detail section taken through the pocket on line IV—IV of Figure 2.

Figure 5 is a fragmentary view of a portion of a modified form of barber's garment provided with a modified form of pocket.

Figure 6 is a horizontal detail section of the modified form of pocket taken on line VI—VI of Figure 5.

Figure 7 is a vertical detail section of the modified form of pocket taken on line VII—VII of Figure 5.

As shown on the drawing:—

The reference numeral 1 indicates a barber or hair trimming attendant wearing an improved barber's coat, smock or gown preferably constructed of a washable material. The improved coat is represented as a whole by the reference numeral 2 and may be of any selected design, length or size such as are commonly furnished by barber coat supply service companies who rent out the coats and provide laundry service in connection therewith. The coat 2 may be provided with a belt 3 or with any other suitable means such as buttons for the purpose of closing the coat. The improved coat is also provided with a plurality of inner and outer sanitary pockets of different sizes which are secured in convenient locations on the garments. The improved pockets may be of the hidden or exposed type and may be of any desired size and shape. In the present showing an inner upper pocket and lower outer pockets of the patch or sport pocket type are shown. Each of the sanitary pockets comprises a patch or piece of material 4 which is cut out to a desired shape and is stitched or otherwise secured to either the inner or outer sides of the body portion of the garment 2 along the top edge 5, along one side edge 6 and along the bottom edge 7 as clearly illustrated in Figure 2. The outer side edge of the pocket has the lower portion 8 thereof stitched to the coat leaving the upper section 9 free from attachment to afford a side or vertical opening into the interior of the pocket. If preferred, all of the pockets may be of the inner or enclosed type and are accessible through vertical entrance slots provided in selected locations in the garment.

Figures 5, 6 and 7 illustrate a modified form of the improved barber's coat, smock or

gown in which the reference numeral 10 indicates the body portion of a garment having an upper slot 11, a lower slot 12, and a side slot 13 provided therein with the margins of said slots reinforced with braid or tape. The top and bottom slots 11 and 12 are opposite one another and determine the height of the pocket. The side slot 13 extends upwardly from adjacent one end of the lower slot 12 to a height approximately half the height of the pocket.

The pocket proper comprises a piece of material 14 having the inner longitudinal or side margin thereof stitched or otherwise secured to the body portion 10 of the coat by stitching 15 or the like. Formed on the upper margin of the pocket piece 14 is an upper flange or flap 16 which is adapted to be projected upwardly through the upper slot 13 and is attached to the inner side of the garment by means of buttons 17 or the like. When buttons are used the flap 16 is provided with suitable button holes to permit attachment of the flap. The lower margin of the pocket piece 14 is provided with a lower flange or flap 18 which projects through the lower slot 12 of the garment and is then bent upwardly to close the lower end of the pocket. The flap 18 is provided with button holes to permit the same to be removably attached to buttons 19 secured on the inner side of the garment. As clearly illustrated in Figure 5 the pocket piece 14 is also provided with a side flange or flap 20 which projects through the side slot or opening 13 and is then bent over to close the lower portion of the outer side of the pocket. The flap 20 is provided with button holes to permit the same to be buttoned on buttons 21 secured on the inner side of the garment. The upper portion of the outer side of the pocket piece 14 is provided with an extension or flap which is bent inwardly and stitched to the rear side of the pocket to provide a reinforced margin or hem affording a mouth-piece or entrance for the improved pocket. The hemmed portion 22 is provided with button holes 23 to permit the upper and lower ends of the mouth-piece of the pocket to be engaged on buttons 24 secured to the outer side of the garment.

It will thus be noted that the modified form of pocket illustrated in Figure 5 is permanently attached to the garment 10 only along the sewed edge 15 thereby affording an arrangement whereby the buttons on the margins or flaps of the pocket may be readily unbuttoned or released, allowing the pocket to be opened or reversed. When the pocket 14 is unbuttoned, the interior of the pocket may be thoroughly cleaned of any hair particles or any other foreign matter which may accidentally find its way into the pocket through the vertical side opening thereof.

In the form of barber's coat or garment il-

lustrated in Figures 1 to 4 inclusive, it will be noted that the pockets may be of either the hidden or exposed types which are closed at the top and are provided with side openings for the purpose of preventing the entrance of small particles of hair and the like into the pockets during hair cutting or trimming operations. In the modified form of pocket illustrated in Figure 5, it will be noted that the pocket is also provided with a vertical side opening and in addition is adapted to be unbuttoned to permit the pocket to be hingedly or pivotally swung about the sewed seam 15 to expose the inner surfaces of the pocket to permit thorough cleaning thereof in case any hair particles should find their way into the interior of the pockets. The improved barber's garment having pockets with side openings and closed tops affords a decided improvement in garments of the class described, which are thoroughly sanitary in that the improved pockets of these garments are so arranged that the accumulation of hair particles resulting from the trimming or cutting of hair is practically eliminated with the result that the interiors of the garment pockets are kept clean so that the instruments and articles used by barbers and beauty parlor attendants will not be subjected to contact with the cut hair particles of different persons. It will thus be noted that the spreading of disease is thus greatly reduced by the provision of barber's garments with the improved side opening pockets instead of the old types of pockets which are opened at the top and permit the accumulation of hair clippings and other foreign matter during the use of the barber's coat.

It will of course be understood that various details of construction may be varied through a wide range without departing from the principles of this invention, and it is therefore not the purpose to limit the patent granted hereon otherwise than necessitated by the scope of the appended claims.

We claim as our invention:

1. The combination with a slotted garment, of releasable pockets thereon closed at the top and having side entrance openings therein, and means on said pockets co-acting with the garment slots for securing the pockets in place.

2. A garment comprising a slotted body section and a plurality of side opening pockets thereon, each of said pockets being permanently secured to the body section along one side and having flaps formed on the opposite side, top and bottom removably projecting through the slots and attached to the body section.

3. A hair cutter's garment comprising a coat having slots therein, a pocket thereon having a side opening and also having one margin thereof permanently secured to the coat, means on said pocket for projection

through the slots in the coat, and fastening means for removably securing said means to the coat.

4. A garment of the class described comprising a coat having slots therein, a side entrance pocket having one margin thereof secured to the coat, a plurality of flaps formed on the pocket and projecting through the coat slots, and means for removably securing the flaps to the coat.

In testimony whereof, we have hereunto subscribed our names at Chicago, Cook County, Illinois.

ISADORE GOLDMAN.

JACOB COHEN.
